UNITED STATES PATENT OFFICE.

JOHN R. LOSEY, OF PLYMOUTH, INDIANA.

HITCHING-POST.

SPECIFICATION forming part of Letters Patent No. 651,466, dated June 12, 1900.

Application filed March 19, 1900. Serial No. 9,240. (No model.)

To all whom it may concern:

Be it known that I, JOHN R. LOSEY, a citizen of the United States, residing at Plymouth, in the county of Marshall and State of Indiana, have invented certain new and useful Improvements in Hitching-Posts; and I do hereby declare that the following is a full, clear, and exact description of the same, reference being had to the annexed drawings, making a part of this specification, and to the letters of reference marked thereon.

The present invention has reference to that class of extensible hitching-posts adapted to be let down into a hollow casing below the surface of the ground, whereby said post will be out of the way when not in use and capable of being elevated into position when required to hitch a horse or other animal thereto.

The invention has for its object to provide a simple, strong, and durable hitching-post of the above character that can be easily operated in lowering or extending it, as circumstances require; and it consists in a hitching-post constructed substantially as shown in the drawings and hereinafter described and claimed.

Figure 1 of the drawings is a sectional elevation of a hitching-post constructed in accordance with my invention, showing the post depressed or lowered out of the way when not required for use; Fig. 2, a similar view showing the post elevated or extended in position for use; Fig. 3, a detail perspective view of the tubular post, showing it detached from the hollow casing; Fig. 4, a horizontal section taken on line 4-4 of Fig. 1; Fig. 5, a similar view taken on line 5-5 of Fig. 1; Fig. 6, a detail view of the supporting-bar which sustains the post when in a lowered position; Fig. 7, a detail sectional view, on an enlarged scale, of the spring-actuated latch employed for locking the post in a lowered position when not required for use, as indicated in Fig. 1.

In the accompanying drawings, A represents the hollow casing, having connected at its lower end a suitable anchor B, which has a screw-threaded mortise *a* to engage with the screw-threaded end *b* of the casing. This casing is secured in the ground a suitable distance, with its upper end extending above the curb or surface of the ground, (indicated at X,) as shown in Figs. 1 and 2 of the draw-

ings, said casing being of any suitable length and diameter as found best adapted to the purpose. Upon the interior of the casing A is a circumferential shoulder, which forms a stop *c* near the upper end of said casing, the shoulder being preferably integral therewith. 55

Upon the interior of the casing A and extending lengthwise thereof is a bar C, its upper and lower ends serving, respectively, as a support and a stop to sustain the tubular post D in its extended or raised position, as shown in Fig. 2 of the drawings, and preventing it being elevated or raised after the post 65 has been unlatched without rotating the post the required distance.

The tubular post D is screw-threaded at its upper end for securing thereto a suitable head E, which may be ornamental or plain, as 70 shown, and the lower end of the post has secured thereto a segmental locking-flange *d*, which flange abuts against the lower end of the bar C, as shown in Fig. 1 of the drawings. The post D, near its upper end, has a suitable opening *e*, through which access may be had to the snap-hook *f* upon the end of the hitching rope or chain F and enable the chain to be drawn out for use when the hitching-post is extended or raised. A suitable weight 80 *g* upon the lower end of the rope or chain F automatically draws the same down in the post when released or when not in use, a tubular support *h* in connection with the disk *i* preventing the hitching rope or chain from 85 going too far down in the tubular post. The tubular support *h* is secured to the interior of the post D, and although I have shown the support in the form of a tube or short section of pipe any suitably-shaped support may be 90 substituted for that shown and any means may be used in place of the disk *i* upon the snap-hook *f*, as found most desirable.

Within the hollow casing A, at the lower end thereof, is a spiral spring G, its lower end resting in the mortise *a* of the anchor B and its upper end bearing against the lower end of the tubular hitching-post D, this spring serving to force said post upward into position when the same is released. 95

The post when not in use is securely locked in a lowered or depressed position, as shown in Fig. 1 of the drawings, by means of what I term a "spring-actuated latch," consisting 100

of the bolt I and guard-plate H. This bolt I is formed upon the upper end of a suitable spring-shank k, which shank at its base is seated in a recess l upon the interior of the head E, the guard-plate H being secured at its lower end to the base of the shank and at its upper end provided with a hole m to enable the bolt I to enter and extend through a sufficient distance to engage the circumferential flange n upon the upper end of the hollow casing A, as shown in Fig. 1 of the drawings, thereby holding and locking the post D in a lowered position out of the way when not in use.

15 In Fig. 7 is shown a detail view of the spring-bolt, the guard-plate, and the key, showing them in the position they will assume when the post is unlocked and released from the casing. The guard-plate H, as should be understood, lies flat against the hollow casing A when the post D is in a lowered position, the bolt I engaging the casing directly under the flange n and locking the post against being extended.

25 When it is desired to withdraw the bolt from engagement with the flange of the casing, the key J is inserted in the keyhole in the head and extends to one side of the spring-shank k of the bolt I, the extremity of heel p of the 30 key engaging a perforation or hole in the guard-plate H to support the key in proper position while being turned. As the key is turned to bring the cam o thereon to the position as indicated in Fig. 7 of the drawings 35 the cam when being brought to such position will force outward the spring-shank k of the bolt I and in turn force back the bolt out of engagement with the flange n upon the end of the casing A. The post after being thus 40 unlocked cannot be raised until the same is turned on its axis a suitable distance to bring the space between the ends of the locking-flange d on line or opposite the bar C, when the spring will force upward the post D to 45 the position shown in Fig. 2 of the drawings, the circumferential shoulder c upon the interior of the hollow casing A forming a stop against which the flange d comes in contact to prevent the post from being forced too far 50 upward.

I do not wish to be understood as limiting myself to any special form of spring-latch, as any key-operating spring-latch or any latch adapted to be operated by a suitable key may be substituted for that shown, and any spring- 55 actuated post or a post that is adapted to automatically force itself upward when released may be used in place of that illustrated in the drawings.

Any changes that would come within ordinary mechanical construction may be resorted to without departing from the essential features of the invention.

Having now fully described my invention, what I claim as new, and desire to secure by 65 Letters Patent, is—

1. A tubular hitching-post, comprising a hollow casing, a bar upon the interior thereof extending longitudinally with the post to form a support and stop at its ends respectively, a circumferential shoulder to form a stop near the upper end of the casing, a spring-actuated tubular post having a segmental locking-flange at its lower end, a suitable hitching cord or chain contained in the tubular post, and a spring-actuated latch for locking the post in a lowered position, substantially as and for the purpose set forth. 75

2. In a tubular hitching-post, a suitable casing having a circumferential flange at its upper end, an extensible and spring-actuated post provided with a hitching-chain, a suitable head connected to the upper end of the post, and a spring-latch device upon the inner side of the head and adapted to engage 85 the flange on the casing, said latch comprising a guard-plate having a hole at its upper end, a bolt adapted to extend through the opening in the plate and engage with the flange on the casing, said bolt having a spring- 90 shank and suitable means for releasing the bolt, substantially as and for the purpose set forth.

In testimony that I claim the above I have hereunto subscribed my name in the presence 95 of two witnesses.

JOHN R. LOSEY.
